United States Patent Office

Des. 191,895
Patented Dec. 5, 1961

191,895

ASH TRAY

Justin Sturm, Sylvan Road, Westport, Conn.

Filed Mar. 30, 1960, Ser. No. 59,952

Term of patent 14 years

(Cl. D85—2)

The FIGURE is a perspective view of an ash tray, showing my new design.

I claim:

The ornamental design for an ash tray, substantially as shown.
